(57) **CLAIM**

The ornamental design for in vitro diagnostic medical device, as shown and described.

DESCRIPTION

FIG. 1 is a top, front and left side perspective view of the in vitro diagnostic medical device according to my new design; FIG. 2 is a top, rear and left side perspective view thereof; FIG. 3 is a left side elevational view thereof; FIG. 4 is a right side elevational view thereof; FIG. 5 is front elevational view thereof; FIG. 6 is a rear elevational view thereof; FIG. 7 is a top plan view thereof; and, FIG. 8 is a bottom plan view thereof.

The broken lines in FIG. 8 illustrate portion of the in vitro diagnostic medical device that forms no part of the claimed design.
